UNITED STATES PATENT OFFICE.

JAMES WATSON HARRIS, OF ASHLAND, OHIO.

DOOR-HANGER.

No. 873,230.

Specification of Letters Patent.

Patented Dec. 10, 1907.

Application filed March 20, 1907. Serial No. 363,455.

To all whom it may concern:

Be it known that I, JAMES WATSON HARRIS, a citizen of the United States, residing at Ashland, in the county of Ashland and State 5 of Ohio, have invented a new and useful Door-Hanger, of which the following is a specification.

This invention relates primarily to door hangers of that type in which car, barn and 10 similar doors are suspended from an overhead track and movable endwise to open and close the entrance to structures which they guard; and it has for its object to provide an improved track and supporting brackets 15 therefore, whereby the track is retained in position without other fastening means than that afforded by the bracket itself, which latter while securely upholding the track will permit it to be longitudinally adjusted 20 therein.

Another object of the invention resides in the hanger which travels in the track and supports the door. This hanger is provided with a flange head supported on balls carried 25 by the track, and has its lower end slotted to receive a yoke or hook attached to the door in such manner that the latter may be drawn bodily away from the side of the car or building when it is to be operated, thereby giving 30 perfect freedom of movement without fear or danger of its sliding against the wall of the structure, and when moved to close the opening of a building or car it can be pushed as closely and as tightly against the wall as 35 doors now in use.

A further object of the invention is its adaptability for use as the guideway and carrier of an overhead conveyer, such as are employed in factories and other large establishments to carry bulky objects from place to 40 place therein.

With these and other objects in view the invention consists in the novel construction, combination and arrangement of parts hereinafter described and definitely claimed.

Figure 1 is a side elevation of a portion of a car, showing the door thereof supported by the improved door hanger. Fig. 2 is an enlarged end view showing the supporting bracket, the track carried thereby, the hanger and portion of a door suspended therefrom. Figs. 3 and 4 are detail views in section representing different positions of the door with respect to the hanger. Fig. 5 is a perspective 55 view of a modified form of the device.

Similar numerals of reference indicate the same parts in all the figures.

Directing the attention particularly to Fig. 1, the side of a car or other structure indicated by the numeral 1, is provided with a 60 closure or door 2, constructed in any well known way. Above the door 2 and parallel with its top edge is a rail or track 3, shown more clearly in Fig. 2, supported at intervals by brackets 4. At the top of the door near 65 each end, or at more frequent intervals if necessary, are bolted or otherwise fastened, yokes 5 (see Figs. 2 to 4). The yokes 5 are slidably mounted in an opening 7 formed in the lower end of the hanger 8, the upper end 70 of said hanger engaging with the track 3 and movable therein.

The track 3 may be made of cast metal of the form substantially that shown in Fig. 2, but by preference it will be made of strips of 75 sheet steel bent into shape by suitable dies. An end view of the track shows a flat top 9, of suitable width bent downwardly at 10 and 11 to form sides 12 and 13 inclining inwardly towards the center of the track. The ends 80 of each side 12, 13 are bent upwardly at 14 and 15 to form the narrow inclined portions 16, 17. The sides 12, 13 in connection with the upturned portions 16, 17 form V-shaped ball tracks in which travel balls 18, seated in 85 the under side of the flanged head 19 of the hanger 8. As clearly illustrated in Fig. 2 the head 19 of the hanger 8 projects equally on opposite sides of the upright portion of the hanger overlying the ball track 20. By 90 making a slight depression in the under surface of the head 19 on each side of the hanger the balls 18 will be retained in place and a simple, easily operating bearing be produced. It is also to be observed that the flat top 9 of 95 the track affords a cover for the ball tracks and hanger and as the sides 12, 13 and the narrow portions 16, 17 incline downwardly and toward each other, such rain and moisture as falls on the track will drip off or run 100 off therefrom and drop from the bends 14 and 15 making it very difficult for dampness to penetrate the interior of the track.

The brackets 4 are substantially of the outline represented in Fig. 2 comprising an 105 outstanding central portion 21 and an upper and lower foot 22 which latter are bolted or otherwise fastened to a wall or other part of the structure. The under side of the central portion or body 21 of the bracket is shaped 110

to the outline of the track. The socket thus formed embracing over one-half of the sides 12, 13 of the track, thereby giving it a firm support to the downward pull of the suspended door 2. By shaping the track sockets in the bracket in the manner described, it is not necessary to have them fit immovably around the track, but they may be sufficiently large to allow end movement of the track and at the same time hold it sufficiently firm for all necessary purposes.

The hanger 8 is provided with a head 19, as heretofore stated, and an opening 7 near its lower end through which the yoke 5 is passed. The width of the hangers 8 may be little greater than the yoke 5 as represented in Fig. 1, or a single hanger may be used extending the width of the door.

The yoke 5 is attached to the upper part 20 of the door and projects a short way above its top side, the depending portions 25, 26 being fastened, respectively to the outside and inside of the door. The top of the yoke 27 is flat and hangs from the opening 7 in the hanger 8. In Fig. 2 the door 2 is shown suspended from the hanger 8 in an intermediate position. When the door is to be opened it is drawn outwardly until the inner end of the yoke 26 rests against the hanger 8 as shown in Fig. 3, which movement brings the door away from the side wall 1 and permits it to be moved without danger of striking said wall; but after the door has been closed it is pushed toward the wall until the depending portion 25 of the yoke rests against the hanger 8, as shown in Fig. 4. This brings the door close against the wall and when locked in position will remain in close contact therewith.

If desired the yoke 5 may be replaced by the hook 6 shown in Fig. 5, which latter is fastened to the outer side of the door, so that the lateral extension 28 of the hook will project over the top of said door but a short distance above it and extend through the hole 7 of the hanger, being retained therein by a depending flange 29 on the hook. In the same figure is shown the hanger extending the full width of the door as heretofore mentioned.

The hanger 23 in this modified form is made of sheet steel bent upon itself to form the upright portion of the hanger, the fold of which is at the bottom. The ends are turned laterally in opposite directions to form a head which slides on the inturned ends of a flat tubular track 24.

Having thus described the invention what is claimed is:—

1. In a door hanger the combination with

a covered track or rail having inwardly inclined depending sides and inwardly upturned lower edges between which is left a space, of a suspending bracket for said track having its under sides socketed to guide and embrace the upper part of said track, a hanger supported on the upturned ends of and within said track, and a door suspending member loosely attached to said hanger to permit of independent movement of said suspending member in a direction transverse to said track.

2. In a door hanger, the combination with a covered track having inwardly inclined depending sides and a ball track formed in the lower end of each of said sides, a space being left between said ball tracks, of a hanger having a flanged head traveling within said track and provided with ball seats on its under surface, and a door suspending member loosely supported by said hanger to permit of independent movement of said member in a direction transverse to said track.

3. In a door hanger the combination with a covered track having inwardly inclined depending sides and a ball track formed in the lower ends of each of said sides separated by a space, of a hanger having a flanged head traveling within said track and provided with ball seats on its under surface and an opening in its lower end and a yoke attached to the door and adapted to slide in said opening transversely of the track.

4. In a door hanger the combination with an over head track, of a hanger supported therein and movable in a longitudinal direction, and a yoke from which the door is suspended and adapted to slide freely back and forth in an opening in said hanger in a direction transverse to the movement of said hanger, whereby said door is carried bodily in a straight line to and from the opening to be closed.

5. In a door hanger, a track therefor, made of sheet metal and having a flat top, downwardly extending sides inclining towards the center of the track and upwardly inclining edges at the bottom of said sides, said inclined edges in connection with the sides of the track form two grooves which serve as ball tracks.

In testimony that I claim the foregoing as my own, I have hereto affixed my signature in the presence of two witnesses.

JAMES WATSON HARRIS.
